CLIO B. YAW, OF ARLINGTON, NEW JERSEY, ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,071,495.

Specification of Letters Patent.

Patented Aug. 26, 1913.

Application filed January 27, 1911. Serial No. 605,097.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My invention relates to paper feeding mechanism for typewriting machines and has for its object to provide novel paper clamping, guiding, and stop devices, and which are especially adapted to facilitate the execution of various kinds of typewriting matter.

To the above and other ends my invention consists in the features of construction, combinations of devices and arrangements of parts hereinafter described and particularly pointed out in the claims.

My invention is shown as applied to a No. 10 Remington front-strike typewriting machine, but various features of the invention may be employed in other styles of typewriting machines.

The embodiment of my invention herein shown was especially designed for use in connection with work forms of the character employed by some gas companies which 30 make use of a record sheet which is kept for reference a period of years and print the statistics or items of the monthly bill intended for the customer simultaneously with the corresponding entry on the record sheet. 35 These month to month statistics occupy each only a single line and this line occupies always the same position on the monthly bills although its position on the record sheets will vary, depending on the number 40 of prior entries. Accordingly the record sheets may be pushed or fed around the platen from back to front until the proper position is attained for writing, as by turning the platen and causing it to coöperate 45 with the usual feed rollers, or otherwise. The bill sheet, however, is introduced at the front of the platen and I provide special contrivances for guiding, positioning and controlling the same. These devices 50 comprise in the present instance a device plate-like in form and angular in cross section and hinged to the traveling carriage below the platen so that the upper edge of said device may coöperate with the platen along

the same below the printing line to clamp 55 the bill sheet to the platen, the clamping effect being obtained by a spring associated with said device. The device has secured to it a rearwardly extending arm provided with a roller or wheel which coöperates with 60 a cam device fixed to the frame so that at a predetermined point in the leftward travel of the carriage the wheel rides up on the cam, overcoming the spring and swinging the device away from the front face of 65 the platen, providing a sort of pocket into which the bill sheet may be readily entered and pushed down until its leading edge is arrested by the V-shaped lower end of the device which thus serves as an end stop, 70 the upper portion being in the nature of a paper guide or deflector. As soon as the bill has been properly positioned in this way the carriage is moved rightward until arrested by the margin stops in position for 75 beginning the line of writing on the bill sheet, the same being reproduced on the record sheet through an interposed carbon sheet. During the rightward movement aforesaid the wheel or roller separates from 80 the cam, thus permitting the spring to force the device against the platen to clamp the bill sheet thereagainst. The combined clamp and the deflector device, it will be 85 observed, is automatically operated independently of the rotary turning movements of the platen and during and at predetermined points in the travel of the carriage and the platen carried thereby. In prior 90 automatic clamps for typewriting machines it has been necessary to turn the platen in order to open and close the clamp.

My invention will be more specifically described in connection with the accompanying drawings wherein—

Figure 1 is a fragmentary front elevation, partly in section, of the upper part of a Remington No. 10 typewriting machine embodying my invention, only so much of the machine being shown as is necessary 100 to a clear understanding of said invention. Fig. 2 is a perspective view of the paper controlling device as it appears when detached. Fig. 3 is a transverse sectional view of the carriage, platen and associate devices, 105 said view also showing the upper part of the machine frame. Fig. 4 is a transverse view corresponding to Fig. 3 but omitting some

of the parts illustrated in said figure and showing other parts in different relationships.

As appears in Figs. 1 and 3, the frame of the machine comprises frame portions or posts 1 supporting a top plate 2 from which rise standards 3 carrying grooved trackways 4 which coöperate through anti-friction rolls 5 with a truck comprising front and rear bars 6 and 7 and connecting end bars 8. The truck supports and is connected with, through links 9, a shiftable platen frame which comprises end bars 10, a connecting bar 11 and a frame rod 12. A platen 13 has an axle 14 which bears in the end bars 10 and is provided with the usual finger wheels 15 by which the platen may be turned or rotated both forward and backward. Line spacing devices (not shown) of the usual or other suitable character are also employed for rotating the platen step-by-step forward for spacing between the lines of writing. The platen frame and the platen carried thereby are adapted to be lifted up and down on the truck to change case in a manner well understood, while the carriage comprising the truck and the platen frame is adapted to move endwise back and forth to space between letters and return the carriage for beginning a new line of writing. The platen 13 may be equipped with paper feeding devices comprising a feed roller 16 of ordinary pattern, said feed roller coöperating with the platen at its rear under side to feed paper when the platen is turned. The feed roller is releasable by devices (not shown) mounted on a hand controlled rock shaft 17 which bears in the end bars 10. A paper apron or deflector 18 is supported on said rock shaft and curves thence around the platen, terminating at a point below the printing line at the front side thereof. The usual paper table is omitted from the drawing but is preferably employed. Coöperative with the platen above the printing line is a pressure device comprising a longitudinally extending rod 19 provided with rearwardly extending arms 20 which are provided with hubs 21 bearing on the rod 12. A spring 22 (Fig. 1) tends to maintain the pressure rod 19 in coöperation with the platen while said rod 19 may be swung away from the platen against the spring 22 by a finger piece 23 on one of the hubs 21. In order to accommodate and coöperate with the novel devices embodying my invention, the apron 18 is cut away at its front side near the left end of the platen, as indicated at 24. At the left-hand edge of the cut-out 24 the apron 18 has a forwardly bent portion 25 which serves both as a side guide and controller for the bill sheet, as hereinafter explained. Adapted to register 65 with the cut-out is a novel paper controlling

device which is shown detached in Fig. 2 and is designated as a whole by the numeral 26. The body of said device is preferably made of sheet metal and comprises a clamping and deflector plate 27, the upper portion of which is slightly concave to conform to the platen surface. The portion below the concave is straight and at its lower end is slotted or cut to provide tongues or strips. Two of these tongues 28 are bent rearward 75 and upward at an acute angle from the body portion 27, the parts 28 acting as leading edge stops, as hereinafter explained. The stop portions 28 are separated by a tongue or strip 29 which, with the end tongues 30, is bent or curled forward to provide openings which receive a bearing rod 31 (Figs. 1 and 3). The rod is made separate to facilitate the assembling of the parts but after said rod is mounted in its bearings on the machine it is preferably secured in fixed relationship to the controlling device 26 as by soldering the rod to the bearing portions 29 and 30. The end portions of the rod 31 project beyond the ends of the device 26 and bear in lugs or brackets 32 which are screwed at 33 to the front face of the bar 11 of the platen frame. Spacing collars 34 secured to the rod 31 between the brackets 32 and the adjacent curled ends 30 prevent endwise movement of the rod 31 and the device 26 but permitting the rod to turn in its bearings to rock or swing the portion 27 of the device forward and away from the platen, the rod 31 serving in effect as a rock shaft. A wire spring 35 is coiled around the left-hand end portion of the rod or rock shaft 31 where it projects beyond the bracket 32. One end of said spring is secured to said 105 bracket while the opposite end engages in a collar 36 fast on the rod, the effect of said spring being to maintain the upper curved portion of the plate-like body 27 normally in engagement with the platen or with the 110 work sheet, the friction due to said spring causing the part 27 to clamp the work sheet to the platen.

In order to swing the paper controlling device away from the platen to facilitate the introduction of the work sheet, automatic devices are provided which comprise an arm or finger 37 secured to the right-hand front lower portion of the part 27 by a screw 38 and curved rearward under the rod 31 carrying at its rear end an engaging device, roller or wheel 39. Said wheel is at the opposite side of the axis of rotation from the plate 27 and is adapted to coöperate with an actuating device which is 125 fixed to the frame of the machine. Said device comprises a rectangular bar or track 40 which is arranged on the top plate lengthwise of the platen and in the path of the roller 39. The bar 40 is bent or inclined 130

downwardly at its right-hand end as indicated at 41 (Fig. 1). Suitably secured to the rear face of the bar 40 is a vertical plate 42 provided with horizontally bent 5 ears 43 which receive screws 44, said screws securing the plate 42 and bar or track 40 to the top plate 2. It will be apparent that the spring 35 will maintain the device 26 in operated position until the platen and the 10 traveling carriage are moved endwise far enough to bring the roller 39 into coöperation with its actuating device. When this occurs the roller will ride up on the inclined or cam edge 41, and, as leftward movement 15 is continued, will roll along the track 40. This tract is at such an elevation that the roller will be lifted far enough to rock the device 26 on its pivotal axis 31 to the position shown in Fig. 4, from which it will be 20 observed that the body part 27 has been swung some distance away from the platen so as to provide a ready entrance for the work sheet. When the clamp is opened, or, put in another way, when the deflector is in 25 the paper receiving position, as indicated in Fig. 4, the body portion 27 will incline downward and rearward from a point somewhat below the printing line on the platen to a point some distance under the platen 30 axis. The location of the pivotal axis 31, it will be observed, is substantially in the vertical plane of the platen axis 14, and the stop portions 28 extend substantially vertically somewhat behind said vertical plane. 35 While these stop portions 28 are preferably part of the device 26, they need not necessarily be so made. Let it be assumed that the record sheet designated in Fig. 4 as 45 has been entered in the machine at the back 40 of the platen and has been fed or pushed around to the proper position for receiving the line to be written. This advancing movement may be accomplished by turning the platen, causing the platen and the feed 45 roller 16 to coöperate to advance the record sheet 45, the same passing between the platen and the apron 18 and being guided under the pressure rod 19. As has been stated the record sheet 45 of the character specifically 50 referred to accommodates single-line monthly entries. It is one of the purposes of my invention to enable the entries on the record sheets to be duplicated at the same time that the corresponding lines on the bill sheets 55 are written, and accordingly a carbon inlay 46 is preferably advanced around the platen with the record sheet 45 and outside the same. For the sake of clearness the record and carbon sheets are shown separated from 60 the front face of the platen, but it will be understood that these sheets, together with the bill sheets, may be controlled above the printing line by the pressure rod 19. The paper controlling device 26 being open, as 65 shown in Fig. 4, the bill sheet 47 is next inserted at the front of the platen between the same and the inclined plate 27, said bill sheet contacting at its left-hand edge with the side guide or gage 25 and being pushed down until it is arrested by the gage- 70 devices or leading edge stops 28 which form with the body portion 27 a V-opening. The parts are so proportioned and arranged that when the bill sheet is arrested by the stops 28 it will be in a position such that 75 the blank line which is to be filled in is in register with the printing line. The bill having been positioned against the stops or gages 28 as above explained, the carriage is moved rightward until arrested by the 80 margin stops (not shown). During the rightward movement the roller 39 will ride down off the cam or incline 41 and the spring 35 will shut the clamp, causing the portion 27 to clamp or press the bill sheet 85 to the platen. Prior to the clamping operation, the bill sheet will be forced to move endwise with the platen by the side guide or abutment 25 which engages the left-hand edge of said bill sheet. After the arrest of 90 the platen by the margin stops the blank line on the bill sheet will be filled in by operating the usual printing instrumentalities (not shown), the printing being duplicated through the carbon inlay on the record 95 sheet 45. During the filling in of the blank the carriage will move step-by-step leftward and the roller 39 will approach the cam 41. When the writing has been completed the carriage may be released by operating the release key (not shown), and permitted to move leftward under the pull of the usual carriage power or spring drum, causing the roller 39 to ride up on the track 40 and open the combined clamping, guiding and stop device 26. The bill sheet may now be withdrawn and a fresh one inserted. A new record sheet may be introduced independently whenever necessary. In some 100 systems of work the same record sheet will be employed for a series of successive bill sheets. As soon as the work sheets are positioned the carriage is again retracted until arrested by the margin stops when the 105 operations above outlined are repeated. 110

It will be observed that by my present invention I combine a rotary platen with a paper clamp and means for automatically operating the clamp without rotating the platen, this arrangement being particularly 115 advantageous where single line entries only are made on the work sheets; that the clamp is mounted independently of the platen on the platen carrier or carriage; that the clamp is automatically opened by a fixed 120 device or cam on the carriage and is closed automatically by a spring device, the cam and the spring operating as described during endwise movements of the platen carrier and platen, the cam being on the ma- 125 130

chine frame and the spring on the platen carrier; that the clamp travels endwise with the traveling carriage and platen; that said clamp is pivotally mounted or hinged below the platen; that a paper controlling device is provided which combines the functions of a paper clamp, a paper guide or deflector and an end stop for the leading edge of a sheet as it is introduced into the machine, 5 the sheet in the present instance being introduced at the front side of the platen, and moved backward or oppositely to the direction of line spacing movement; and that a device is provided which combines the functions of a side gage or guide for the paper 10 and also of an abutment for forcing the paper to travel with the platen prior to the closing of the clamp.

Various changes may be made without departing from my invention.

What I claim as new and desire to secure by Letters Patent, is:—

1. In a typewriting machine, the combination of a rotary platen, devices for rotating the same, a paper clamp coöperating with the platen to press the paper thereagainst, paper feeding devices coöoperative with the platen at the introductory side thereof; and means for automatically operating said clamp both to clamp and to release the paper independently of said paper feeding devices and also of said platen rotating devices.

2. In a typewriting machine, the combination of a rotary platen, devices for controlling the rotation of the same, a paper clamp mounted independently of the platen, paper feeding devices coöoperative with said platen at the introductory side thereof, and means for automatically opening and closing said clamp independently of said paper feeding devices and also of said controlling devices.

3. In a typewriting machine, the combination of a rotary platen, devices for controlling the rotation of the same, a hinged paper clamp coöoperative with the platen, a main feed roller coöoperative with the platen, automatic means for opening said clamp independently of said main feed roller and also of said controlling devices, and a spring for closing said clamp.

4. In a typewriting machine, the combination of a platen carrier, a platen thereon, devices for controlling the rotary movements of said platen, a paper clamp mounted to travel with said platen and said carrier, paper feeding devices mounted on said carrier and coöoperative with said platen at the under side thereof, and means independent of said paper feeding devices and also of said controlling devices for opening said paper clamp.

5. In a typewriting machine, the combination of a platen carrier, a platen, a paper

clamp movable endwise with the platen and adapted to clamp paper thereagainst, an engaging device connected to said clamp, and means on the frame of the machine for co-operating with said engaging device to open the clamp, said means and said device being caused to engage solely through movement of the platen carrier.

6. In a typewriting machine, the combination of a platen, a paper clamp movable endwise with the platen and adapted to clamp paper thereagainst, an engaging device connected to said clamp, and means on the frame of the machine for co-operating with said engaging device to open the clamp, said means being constantly in the path of said device when the two are disengaged.

7. In a typewriting machine, the combination of an endwise traveling platen, a paper clamp mounted to travel therewith and adapted to clamp paper thereagainst, an engaging device constantly connected to said clamp, and means coöperative with said engaging device for automatically opening said clamp during endwise movements of the platen.

8. In a typewriting machine, the combination of a platen, a traveling carriage on which said platen is mounted, a paper clamp mounted to travel with said carriage and with said platen and adapted to clamp paper against the platen, an engaging device having a support rigid with said clamp, and means for automatically coöoperating with said engaging device during the travel of the carriage to actuate said clamp and cause it to operatively engage with and disengage from the paper on the platen.

9. In a typewriting machine, the combination of a traveling platen, a paper clamp mounted to travel therewith and adapted to clamp paper against the platen, an engaging device connected to said clamp, and a stationary cam constantly in the path of said device when disengaged therefrom and automatically coöperating with said device to open said clamp.

10. In a typewriting machine, the combination of a platen carrier, a platen, devices for controlling the rotation thereof, a main feed roller, a paper clamp mounted on said platen carrier independently of the platen and of said feed roller, and means independent of said devices for automatically moving said clamp both into and out of pressing engagement with said platen.

11. In a typewriting machine, the combination of a platen, a traveling platen carrier on which said platen is rotatably mounted, a main feed roller coöoperative with the platen, a paper controlling device pivotally mounted on said carrier independently of the platen but coöoperative therewith to control paper, said device being also mounted

- independently of said main feed roller, and means for automatically moving said device away from the platen to facilitate the introduction of the paper.
- 5 12. In a typewriting machine, the combination of a platen, a traveling platen carrier on which said platen is rotatably mounted, a paper controlling device pivotally mounted on said carrier independently of the platen but coöperative therewith to control paper, an engaging device constantly connected with said paper controlling device, and a cam on the frame of the machine coöperative with said engaging device for automatically moving said paper controlling device away from the platen to facilitate the introduction of paper. 70
- 10 13. In a typewriting machine, the combination of a platen; a traveling platen carrier on which said platen is rotatably mounted; a paper controlling device pivotally mounted on said carrier independently of the platen but coöperative therewith to control paper; an engaging element connected to said paper controlling device; a fixed cam coöperative with said element for automatically moving said device away from the platen to facilitate the introduction of paper, said cam being constantly in the path of said element when the parts are disengaged; and a spring for automatically closing said device. 85
- 15 14. In a typewriting machine, the combination of a rotary platen, a paper deflector coöperative therewith, a main feed roller coöperative with the platen, and means for automatically moving said deflector away from the platen independently of the main feed roller to facilitate the introduction of the paper. 90
- 20 15. In a typewriting machine, the combination of a rotary platen, a paper deflector coöperative therewith, a main feed roller coöperative with the platen, and means operating independently of the rotation of the platen for automatically moving said clamp away from the platen independently of the main feed roller to facilitate the introduction of paper. 95
- 25 16. In a typewriting machine, the combination of a rotary platen, a paper deflector coöperative therewith but mounted independently thereof, a main feed roller coöperative with the platen, and means operating independently of the rotation of the platen and also independently of the main feed roller for automatically moving said clamp away from the platen to facilitate the introduction of paper. 100
- 30 17. In a typewriting machine, the combination of a rotary platen, a platen carrier on which said platen is supported, a paper deflector pivoted on said carrier and coöperative with said platen, a main feed roller coöperative with the platen, and means 105
- 35 operating independently of the rotation of the platen and also independently of the main feed roller for automatically moving said clamp away from the platen to facilitate the introduction of paper. 110
- 40 18. In a typewriting machine, the combination of a traveling carriage, a platen thereon, devices for controlling the rotation thereof, a paper clamp coöperative with the platen to press the paper thereagainst, and means acting during the traveling movements of the carriage and independently of said devices for automatically operating said clamp both to clamp and to release the paper. 115
- 45 19. In a typewriting machine, the combination of a traveling carriage, a platen, a paper stop, a paper clamp, and means for moving said paper stop and said paper clamp into position to permit the introduction of paper and back again to a position where the paper is clamped by said clamp during traveling movements of said carriage. 120
- 50 20. In a typewriting machine, the combination of a traveling carriage, a platen thereon, devices for controlling rotary movements thereof, a swinging paper deflector on said carriage, and means for moving said deflector away from the platen to facilitate the introduction of paper, said means being brought into action automatically and independently of said devices during traveling movements of said carriage. 125
- 55 21. In a typewriting machine, the combination of a traveling platen, a leading edge paper stop device, and means for moving said stop device into position to coöperate with the paper as it is introduced into the machine, said means operating automatically during traveling movements of the platen. 130
- 60 22. In a typewriting machine, the combination of a traveling platen, a leading edge paper stop device, and means for moving said stop device into position to coöperate with the paper as it is introduced into the machine, said means including a device fixed to the frame of the machine. 135
- 65 23. In a typewriting machine, the combination of a traveling carriage, a platen thereon, a paper stop operative to position paper with respect to the platen but mounted on the carriage independently of said platen, and means operating automatically during traveling movements of the carriage to move said paper stop into position to obstruct the path of the paper when introduced into the machine. 140
- 70 24. In a typewriting machine, the combination of a traveling platen, a paper clamp coöperative therewith, and means operating at a predetermined point in the travel of the platen in printing direction to open said clamp, said means being brought 145

into action solely by reason of the traveling movement of said platen.

25. In a typewriting machine, the combination of a traveling platen, a combined paper deflector and clamp, and means operating at a predetermined point in the travel of the platen in printing direction to move said combined deflector and clamp away from the platen surface, said means being brought into action solely by reason of the traveling movement of said platen.

26. In a typewriting machine, the combination of a rotary platen, paper feeding devices coöperative therewith to feed paper introduced at the rear side of the platen, and an automatic clamp coöperating with the platen to clamp a sheet of paper which is controlled independently of said paper feeding devices.

20 27. In a front-strike typewriting machine, the combination of a platen, paper controlling devices coöperative with the platen to feed paper introduced at the rear thereof, and a separate paper controlling device 25 automatically movable away from the platen independently of said first named devices to receive paper introduced at the front side thereof.

28. In a front-strike typewriting machine, the combination of a platen, paper feeding devices coöperative with the platen to feed paper around the same from back to front, and a paper deflector automatically movable away from the platen independently of said paper feeding devices to receive paper introduced at the front side thereof.

29. In a front-strike typewriting machine, the combination of a platen, paper controlling devices coöperative with the platen to advance paper in the proper path around the same from back to front, and an automatic paper clamp operative independently of said paper controlling devices to clamp 45 to the platen paper introduced at the front side thereof.

30. In a front-strike typewriting machine, the combination of a platen carrier, a platen, feed roller devices, a paper clamp coöperative with the platen at its front side below the printing line, said clamp being hinged directly to said platen carrier and being controlled independently of said feed roller devices, and a pressure device 55 operative with the platen above the printing line.

31. In a typewriting machine, the combination of a platen, and a pivoted V-shaped paper guiding and controlling device movable away from the platen to facilitate the introduction and stoppage of paper and movable toward the platen to bring said paper into close coöperation with said platen.

65 32. In a typewriting machine, the combi-

nation of a platen carrier, a rotary platen thereon, paper feeding devices coöperative with the platen to feed paper when the platen is turned, and a clamping device mounted on the platen carrier directly and independently of any of the paper feeding devices and automatically brought into and out of co-action with the platen independently of turning movements thereof.

70 33. In a typewriting machine, the combination of an endwise traveling platen, a clamp coöperative with the platen, means for automatically operating the clamp at a predetermined point in the endwise travel of the carriage, and an abutment coöperative with the paper to force it endwise with the platen when said clamp is open.

75 34. In a typewriting machine, the combination of an endwise traveling platen, a clamp coöperative with the platen, means for automatically operating the clamp at a predetermined point in the endwise travel of the carriage, and a device serving as a side gage for the paper and also to move the paper endwise with the platen prior to the 80 closing of the clamp.

85 35. In a typewriting machine, the combination of a rotary platen, a device coöperating with said platen to press paper thereagainst, and means operating automatically during endwise movements of the platen in printing direction to move said device into position to permit the introduction of paper between it and the platen, said means being brought into action solely 90 by reason of said endwise movements of the platen.

95 36. In a typewriting machine, the combination of a rotary platen, a pressure device 105 for the paper, rotary engaging element constantly connected with said pressure device and means engageable by said element and operating automatically during endwise movements of the platen to move said device into and out of operative or working 110 position.

115 37. In a typewriting machine, the combination of a traveling platen, a paper guiding device normally lying close to the surface of the platen, and means for moving 120 said device away from the platen so that it forms therewith a pocket or throat to facilitate the introduction of paper, said means operating automatically at a predetermined point in the travel of the platen.

125 38. In a typewriting machine, the combination of a traveling platen, a paper guiding device normally lying close to the surface of the platen, a paper end stop, and means for moving said device away from the platen so that it forms therewith a pocket or throat to facilitate the introduction of paper and exposes the end stop so 130 that the paper when introduced may coöperate with it, said means operating auto-

matically at a predetermined point in the travel of the platen.

39. In a front-strike typewriting machine, the combination of a carriage, a platen rotatable thereon, a paper guide movably mounted on said platen frame and extending upward from the under side of the platen and terminating below the printing line, and means operating automatically during traveling movements of said carriage to move said guide away from the

face of the platen to provide an entrance pocket or throat to facilitate the backward introduction of the paper.

Signed in the borough of Manhattan, city of New York, in the county of New York and State of New York, this 21st day of Jan., A. D. 1911.

CLIO B. YAW.
